UNITED STATES PATENT OFFICE.

MOSHEH EPSTEIN, OF NEW YORK, N. Y.

SUPPORT FOR PRESSER-IRONS.

1,300,939.

Specification of Letters Patent. Patented Apr. 15, 1919.

Application filed January 18, 1918. Serial No. 212,456.

To all whom it may concern:

Be it known that I, MOSHEH EPSTEIN, a citizen of the United States, and a resident of the city of New York, borough of Manhattan, in the county and State of New York, have invented a new and Improved Support for Presser-Irons, of which the following is a full, clear, and exact description.

This invention relates to apparatus of the character disclosed and claimed in Letters Patent of the United States issued to Jerome Ratner, on the 28th day of November, 1916, No. 1,206,466, and of which Letters Patent I am now the sole owner.

Whereas in the previously patented apparatus it was necessary for the operator to lift the presser iron manually and, considering the weight of the iron which is approximately eighteen pounds in ordinary practice, very much labor was necessarily entailed unless the spring tending to lift the iron were made strong enough to assist in this operation, but in which event a considerable portion of the necessary weight of the iron was neutralized by the spring. Among the objects, therefore, of this invention is to provide power means to lift the iron whereby the operator is relieved from such necessity, means being provided to practically automatically render the power lifting means operative.

A further object of the invention is to provide a support for a presser iron of such a character that there is provided in connection therewith automatically operating power means sufficient to hoist the iron far enough to clear the work so that the iron may be transported laterally or out of the way for change or readjustment of the work or garment to be operated upon, means furthermore being provided to relieve the power means from its function while the iron is held by positive means in its elevated position.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which Figure 1 is a side elevation of one form of

my improved apparatus, parts being broken away, the iron being shown in full lines in operating position and in dotted lines in elevated or idle position.

Fig. 2 is a vertical sectional view of the automatic switch mechanism employed in connection with the device in Fig. 1, this figure also indicating a fragment of the iron supporting shank turned out of normal position for the purpose of indicating the form of a groove therein.

Fig. 3 is a detail view indicating the relation of the shank to the supporting dog and switch pin while the device is in the position of Fig. 1.

Fig. 4 is a horizontal sectional view on the broken line 4—4 of Fig. 3.

Fig. 5 is a view of the same parts as are shown in Fig. 3 indicating the shank in its elevated or idle position.

Fig. 6 is a horizontal section on the line 6—6 of Fig. 5.

Fig. 7 is a view of the same parts showing the relative position of the movable parts at the moment that the switch is closed and the iron is being hoisted.

Fig. 8 is a horizontal section on the line 8—8 of Fig. 7.

Fig. 9 is a view corresponding to Fig. 1, but showing a modified form of the invention.

Fig. 10 is a detail view of the switch mechanism in its relation to the shank, the iron and shank being hoisted.

Fig. 11 is a further modification.

Fig. 12 is a still further modification.

Fig. 13 is a modification in which the power means consists of a strong coil spring which replaces the electromagnetic or solenoid power means of the previously described forms.

Fig. 14 is a vertical sectional detail view of the principal part of Fig. 13, but with the shank turned through an angle of 90 degrees and elevated by the spring motor or lifting device into idle position.

Fig. 15 is a horizontal sectional detail on the line 15—15 of Fig. 13.

Fig. 16 is a horizontal section on the line 16—16 of Fig. 14;

Fig. 17 is a sectional detail on the line 17—17 of Fig. 14; and

Fig. 18 is a detail view of a further modification.

Referring now more particularly to the drawings, I show at 20 a well known type

60

of heavy pressing iron having a handle 21 which through a bail 22 and universal joint 23 is connected to a shank 24 adapted to reciprocate in a sleeve 25 and turn through a portion of a circle around the axis thereof. The sleeve 25 is connected rigidly in any suitable manner with the casing 26 of an electromagnet or solenoid 27, the core 28 of which is associated with or constitutes a part 10 of the upper portion of the shank. The casing 26 is connected by means of a neck 29 to the frame of a trolley 30 movable by anti-friction means along an overhead rail or track 31 in a manner broadly the same 15 as in the patent above referred to so that the iron may be manipulated with convenience over the work or out of the way when the work is to be re-adjusted. In this connection it is to be noted that the rail 31 may be of any desired length even though the drawings indicate the same as relatively short. A circuit carrying cord 32 leads to the solenoid and through a switch casing 33 indicated as carried upon the side of the sleeve 25. As indicated best in Fig. 2 one branch 32^a of the circuit wire is connected to a binding post 34, while the other branch 32^b leads to the solenoid 27 and thence through a branch 32^c back to the main line. Any suitable 20 source of energy, not shown, may be used to supply power to the solenoid when the branches 32^a and 32^b are connected which may be done by any convenient and easily controllable means.

35 Referring again to Fig. 2 a preferred means for controlling the circuit comprises a spring contact 35 having one end secured to the binding post 36 from which the branch 32^b leads while the free end of the spring 35 has a resilient tendency to lie in spaced position within the casing 33 from the binding post 34. See Figs. 3 and 5. When in this position the circuit is broken between the binding posts 34 and 36.

40 45 50 55 60 65 70 75 80 85 90 95 100 105 110 115 120 125 130

37 indicates a switch pin projecting inwardly through a hole 38 formed radially through one wall of the sleeve 25 for co-operation with the shank 24. This pin is urged inwardly by virtue of the spring 35. The shank 24 is provided with an L-shaped groove 38 having a horizontal portion 39 and a vertical portion 40. The horizontal portion 39 is indicated as being at least a quarter circle in extent, and the vertical portion is as long as it is required to lift the iron 20 to clear it above the work. When the switch pin 37 bears upon the outer cylindrical surface of the shank it forces the free end of the spring 35 into engagement with the binding post 34 closing the circuit as in Figs. 2 and 7.

For the purpose of explaining the nature and operation of the contact or switch controlling devices I will now explain that 65 with the iron in operating position as shown

in Fig. 1 the switch pin 37 occupies a position with its inner end projected into the upper end of the vertical portion 40 of the L-shaped groove, in which position the contact spring 35 is spaced from the binding post 34. This vertical portion 40 of the groove may be somewhat wider than the diameter of the pin 37, if desired, for the purpose of providing for a slight lateral vibration or oscillation of the iron in practice. At the upper end of the vertical groove 40 there is provided a cam shoulder 41 leading circumferentially or laterally from the groove 40 above and parallel to the horizontal portion 39. See Fig. 8. If the operator, therefore, gives the iron and shank 24 a partial rotation in a counter clock-wise direction as indicated by the arrow on Fig. 3 the pin 37 will be caused to ride up the cam face 41 so as to bear upon the outer cylindrical surface of the shank, causing the closing of the circuit with the immediate result that the now energized solenoid will lift the iron into the position shown in dotted lines in Fig. 1. At this time the spring pressed holding dog 42 will snap into a notch 43 formed in the shank and indicated as located above the L-shaped groove 38. This notch 43 has a flat top and preferably a flat side while the opposite side is cam shaped as indicated in Fig. 4. The purpose of this dog 42 is to sustain the weight of the shank and parts suspended therefrom when the iron is in its idle position. It will be observed that when the shank and iron are hoisted in the direction of the arrow on Fig. 7 bringing the notch 43 into position for the holding dog to snap into it, the switch pin 37 will drop into the horizontal portion 39 of the groove 38, thereby breaking the circuit at the spring 35. Fig. 5 indicates this condition. When the iron is thus hoisted free from the work it may easily be given an impulse so as to move with its supporting trolley along the rail 31 so as not to obstruct the operator's work of readjusting the fabric being pressed. When it is desired to bring the iron back to its position above the work the operator gives the iron and shank a partial rotation in a clock wise direction causing the dog 42 to ride up over the cam face 43' of the notch 43 and bringing the switch pin 37 into the vertical portion 40 of the groove, thus allowing the iron to drop by gravity upon the work. It will thus be seen that the solenoid is energized only for the purpose of lifting the iron and as soon as this operation is effected the circuit through the solenoid is broken and hence there is no waste of energy in this direction. Furthermore the manual operation to effect the making and breaking of the circuit is very slight.

In the form of the invention shown in

Figs. 9 and 10 the rail 31^a is pivoted at 44 at one end while the core 28^a of the solenoid 27^a is loosely connected at 45 to the other end of the rail. In the idle or 5 dead position of the solenoid the rail is held in horizontal position so that the trolley 30 may move in either direction along the same with a minimum amount of effort on the part of the operator. The wires 32^a and 10 32^b are associated with the switch casing 33 in practically the same manner as already described, there being provided a switch pin 37 for the purpose of automatically controlling the making and breaking of the 15 circuit.

The shank 24^a is connected by means of a contractile spring 46 to the upper portion of the sleeve 25^a. This spring is of moderate strength and serves to prevent the 20 dropping of the iron and shank downward with respect to the sleeve under normal conditions. The switch pin 37 projects into a notch 47, as shown in Fig. 9, the circuit thus being broken and the iron being in 25 operating position. To lift the iron the operator gives the iron and shank a partial turn causing the switch pin to ride up at one end of the notch upon the outer cylindrical surface of the shank closing the circuit 30 and thereby causing the hoisting of the iron due to the operation of the solenoid which swings the rail 31^a into the dotted line position in Fig. 9. After this the trolley and its load will roll automatically toward the pivot 44 and upon the lift or upwardly projecting edge portion 31^b of the rail. When the iron and shank are turned again in the opposite direction so that the switch pin 37 can drop into the notch 47 40 the circuit will be broken, but the trolley resting at this time upon the lift 31^b will hold the iron elevated by virtue of the force of the spring 46.

In Figs. 11 and 12 the circuit through the 45 solenoid wire 32 is controlled by a thumb pressed switch 35^a on or adjacent to the handle 21^a of the iron 20. The solenoid 27^b is similar in its action and location to the solenoid 27^a and is connected to the 50 free end of the movable rail 31^c pivoted at 44 at the opposite end. The trolley 30 operates along the rail 31^c and lift 31^b thereof in practically the same manner as above described in connection with Fig. 9. In this 55 form of the invention it is contemplated that the lift 31^b shall be sufficient to hold the iron elevated above the work while the solenoid is dead. The shank 24^b may be swiveled for free rotation in the sleeve 25^b so that the 60 circuit may be closed through the solenoid at any time by depressing the switch button 35^a and which obviously will be broken again on release of the switch button.

In Fig. 12 the solenoid 27^c is supported 65 upon or from the trolley 30 and so acts di-

rectly upon the shank 24^c in somewhat the same manner as in Fig. 1, while a holding dog 42^a carried by the sleeve 25^c is adapted to snap into a notch 43 similar in nature to that described in connection with Figs. 1 70 and 3. When the switch button 35^a is depressed and the solenoid is momentarily energized the iron will be hoisted into the dotted line position when the dog 42^a will snap into the notch 43 so as to hold it in 75 elevated position as shown in dotted lines when the operator removes his thumb from the switch button. After the iron is elevated in this manner the operator by giving a slight impulse thereto will cause the 80 trolley to roll toward the pivot 44 and in so doing the rail 31^a will be tilted upward by means of a coil spring 48 of moderate strength, such strength being sufficient to keep the free end of the rail elevated while 85 the weight is near the pivot but which will not materially affect the mass of the iron when in operating position. The operator, however, on grasping the iron to return it to operating position from the dotted line 90 position may do so readily even though the rail is slightly upwardly inclined when he begins the return movement of the trolley and iron.

Referring now to the last modification in 95 Figs. 13 to 17, the rail 31^d is indicated the same as in Fig. 12, being supported resiliently at its free end by means of the spring 48. The iron 20 is similar so far as its construction and mounting are concerned to 100 the form shown in Fig. 1. The shank 24^d, however, has a telescopic joint 49 with an auxiliary shank 50. This telescopic joint 49 provides for a slight vertical movement of the shank 50 with respect to the notched 105 shank as may be necessary in practice to accommodate the iron to different thicknesses of cloth. The notches 51 and 52 are adapted to coöperate with a pair of dogs 53 and 54 respectively located on opposite sides of the 110 sleeve 25^d, while the notches are indicated as arranged at a quarter turn apart circumferentially of the shank 24^d, but one in a horizontal plane above the other. The notch 51 accommodates the dog 53 for the purpose 115 of holding the iron and connected shanks in elevated position, the top of the notch being flat for this purpose. At least one side, however, of the notch is beveled or cam-shaped as indicated at 51' so that when the 120 shank is rotated the spring pressed dog 53 will be wiped out of the notch so as to bear against the smooth outer cylindrical surface of the shank whereby the dog is released from holding position. The notch 125 52 has a flat lower end which coöperates with the spring pressed dog 54 to hold the shank 24^d down. This notch 52 has a cam-shaped side or edge 52' for the purpose of 130 releasing the dog on a quarter turn of the

shank. These releasing movements will be understood from Figs. 15 and 16.

The motor or power means adapted to automatically lift the iron in this form of the invention consists of a strong coil spring 55 having one end secured adjacent to the trolley 30 and the lower end secured to the upper end of the shank 24^a, the spring being of the contractile type. The power of the 10 spring may be sufficient to hoist the load suspended therefrom or if desired it may be approximately equal to the task imposed upon it so that the weight of the iron and connecting parts will be practically counter balanced. When, however, the spring is contracted as in Fig. 14 it is relieved from supporting the weight by virtue of the dog 53. When the operator desires to bring the iron back into operating position, he rotates the iron and shanks through a quarter turn in the direction indicated by the arrow in Fig. 16, bringing the notch 52 over the 20 dog 54. He then draws directly downward upon the iron until the dog 54 snaps into the notch 52. This action stores full power in the spring 55, but while this power is intended to be sufficient to lift the iron it has no effect upon the iron to interfere with its proper pressing functions so long as the 30 dog 54 has positive engagement in the notch 52. The operator, therefore, may use the iron in the usual manner with its full force on the work along the rail 31^a but when he wishes to hoist the iron he rotates the 35 iron and shanks in the direction indicated in Fig. 15 setting the spring free to lift the iron where it will be held by the dog 53. From Fig. 17 it will be noted that the auxiliary shank 50 is provided with 40 tongue and groove connections 56 so that the rotation of the iron and the shank 50 will cause the rotation of the notched shank for the purposes above indicated.

In Fig. 1 in place of the bail 22 connected directly to the handle 21 I provide a bracket 22^a to which the lifting devices are connected through a knuckle or head 23, but so designed that more freedom is provided for the handle. The lower portion of 50 the bracket has a hook 22^b which engages over a flange 20' of the iron while an adjustable clip 22^c engages beneath the other side of the flange and so locked in place by means of a thumb nut 22^d.

55. The detail of Fig. 18 provides a spring 48' strong enough to lift the bar 31^a at any time if the catch 57 is withdrawn from the

end of it. This catch is spring operated and so snaps over the end of the bar when the bar is drawn downward against the 60 force of the spring. The catch, however, may comprise a core of a solenoid 58 arranged in any convenient circuit so that when the circuit is completed the catch will be drawn out of engagement with the bar 65 leaving the spring free to lift the bar and the parts mounted thereon as already described.

In several of the figures, notably Figs. 3, 5, and 7, there is indicated a safety stop in 70 the nature of a spring operated pin 59 which is adapted to engage against the shoulder of a recess 60 formed in the shank 24, or its equivalent. The recess 60 is indicated as extending entirely around the shank, and 75 hence the automatic action of the pin 59 by virtue of a spring 61 surrounding it will always serve to prevent any possibility of the shank dropping out of the sleeve 25, no matter how awkward or careless the operator may be. This safety stop has no bearing whatever upon the normal operation of the 80 invention.

I claim:

1. The herein described supporting means 85 for presser irons comprising an overhead member, a rigid member connected to the iron and movable upward and downward with respect to the overhead member, electromagnetic means to lift the rigid member 90 and iron, and means to positively hold the rigid member and iron in elevated position independently of the lifting means aforesaid.

2. The herein described support for 95 presser irons comprising an overhead support, a trolley movable thereon, a sleeve carried by the trolley, a shank movable up and down in the lower end of the sleeve, power means within the sleeve to lift the entire 100 weight of the iron connected to the shank, and means acting between the shank and the sleeve to hold the shank elevated.

3. The herein described support for 105 presser irons comprising an overhead rail, a trolley movable thereon, a sleeve connected to the trolley, a shank movable up and down in the lower end of the sleeve, and an electromagnet within the sleeve serving 110 to lift the entire weight of the shank and iron attached thereto, substantially as set forth.

MOSHEH EPSTEIN.

Copies of this patent may be obtained for five cents each, by addressing the "Commissioner of Patents, Washington, D. C."
